Primary Examiner — Susan E Krakower(57) CLAIM

I claim the ornamental design for the multifunctional weight bench, as shown and described.

DESCRIPTION

FIG. 1 is a rear elevational view of the multifunctional weight bench, showing my new design;

FIG. 2 is a front elevational view thereof;

FIG. 3 is a right side elevational view thereof;

FIG. 4 is a top plan view thereof;

FIG. 5 is a bottom plan view thereof;

FIG. 6 is a front perspective view thereof; and,

FIG. 7 is a rear perspective view thereof.
